The ornamental design for a pair of stylized fingerless gloves, as shown and described.

DESCRIPTION

FIG. 1 is a top plan view of a pair of stylized fingerless gloves showing my new design;

FIG. 2 is a top plan view of a left glove shown separately for clarity of illustration thereof;

FIG. 3 is a bottom plan view of a left glove shown separately for clarity of illustration thereof;

FIG. 4 is a right side view of a left glove shown separately for clarity of illustration thereof;

FIG. 5 is a left side of a left glove shown separately for clarity of illustration thereof;

FIG. 6 is a front view of a left glove shown separately for clarity of illustration thereof; and,

FIG. 7 is a rear view of a right glove shown separately for clarity of illustration thereof.

The design consists of a fingerless glove having a first inner layer and a shorter second outer layer that covers the arm from the elbow to knuckle edge and covers the heel of the palm extending around the lower portion of the thumb.

Each layer is individually stitched at the junction between the index finger and the thumb. The broken lines form no part of the design and are for illustrative purposes only. In addition, shading is provided for illustrative purposes only, and does not form any portion of the claimed design.
